(57) **CLAIM**

What is claimed is the ornamental design for a wireless speaker box, as shown and described.

DESCRIPTION

FIG. 1 is a perspective view of the wireless speaker box;

FIG. 2 is a front view of the wireless speaker box;

FIG. 3 is a back view of the wireless speaker box;

FIG. 4 is a left side view of the wireless speaker box;

FIG. 5 is a right side view of the wireless speaker box;

FIG. 6 is a top view of the wireless speaker box; and,

FIG. 7 is a bottom view of the wireless speaker box.

The broken lines in the Figures represent the portions of the design that form no part of the claim.
